UNITED STATES PATENT OFFICE.

CLAUD E. FULLER, OF KANSAS CITY, MISSOURI

METHOD OF TREATING POROUS BLOCKS.

Specification of Letters Patent. Patented Mar. 21, 1916.

1,176,284.

Application filed October 9, 1915. Serial No. 55,063.

To all whom it may concern:

Be it known that I, CLAUD E. FULLER, a citizen of the United States, residing at Kansas City, in the county of Jackson and 5 State of Missouri, have invented a certain new and useful Improvement in Methods of Treating Porous Blocks, of which the following is a specification.

My invention relates to improvements in 10 methods of treating porous blocks.

It relates to the treating of porous paving blocks, such as bricks, consisting in filling the pores of the blocks, with material, such as liquid bitumen, preferably in the form 15 of asphalt, whereby the blocks will be rendered very durable and impervious to moisture, will have their resiliency increased, and when used for street paving will be comparatively noiseless under traffic conditions.

In Letters Patent, Numbers 1,063,964 and 1,063,965, issued to me June 10th, 1913, there are described a method and apparatus for treating paving blocks, in which the blocks 20 are first heated, after which the air is exhausted therefrom, following which the blocks are immersed in liquid bitumen, the blocks being held under pressure greater than atmospheric during such immersion, 25 after which the immersing fluid is withdrawn from the immersing chamber and the blocks permitted to cool, while still under pressure, until the bitumen contained in the blocks has solidified. The cooling of the 30 blocks while held in the immersing chamber under pressure consumes an extended period of time, during which the treatment of other blocks in the same chamber cannot be proceeded with. The treatment under such 35 process and with such apparatus is, therefore, expensive and the production is greatly limited. If the blocks are removed from the immersing chamber to permit of the use of the chamber for the immersion of other 40 blocks, and the blocks which have been immersed are left in the open air, the asphalt coating on the exterior of the blocks will quickly cool and solidify and the blocks will be stuck together in a solid mass.

50 The object of my present invention is to provide a novel and improved method of treatment which will greatly decrease the cost of treatment and by which the output will be largely increased.

55 In my present method of treatment, the

blocks or bricks after saturation with the liquid bitumen, are gradually cooled at a temperature below the melting point of the asphalt and above the ordinary atmospheric temperature, the cooling being effected at 60 substantially atmospheric pressure. As the blocks are gradually cooled, the exterior coating of bitumen will be absorbed into the pores of the blocks as the bitumen solidifies, due to the fact that the coefficient of expansion of the bitumen is greater than that of 65 the blocks or bricks, and due to the fact that the exterior coating of bitumen is retained at a temperature sufficiently high to prevent its solidification until it has been absorbed into 70 the pores of the blocks.

Blocks treated by my present improved method will, when cooled, not stick together, and the output will be largely increased 75 owing to the fact that after one set of blocks has been immersed, another set may be immersed without delay.

In the accompanying drawings, which illustrate an apparatus adapted to carry into effect my improved method, Figure 1 80 is a vertical longitudinal view partly in section and partly in elevation of the immersing chamber, the tank for supplying the same with liquid filling material and parts connected therewith. Fig. 2 is an enlarged 85 vertical sectional view on the line 2-2 of Fig. 1, the car loaded with blocks being omitted. Fig. 3 is an enlarged vertical section on the line 3-3 of Fig. 1. Fig. 4 is a reduced horizontal sectional view of the immersing, pre-heating and cooling chambers 90 and some of the parts connected therewith. Fig. 5 is an enlarged cross section on the line 5-5 of Fig. 4. Fig. 6 is a vertical sectional view on the line 6-6 of Fig. 5. 95

Similar reference characters designate similar parts in the different views.

The chamber in which the blocks are immersed comprises a horizontal metal cylinder 1 having its inner end closed and provided at its outer end with a swinging door 2, which is preferably hinged at its upper edge and is adapted to be swung upwardly to the open position by means of a suitable block and tackle 3, Fig. 1. The door 2 is 105 provided with suitable clamping devices 4 for holding it tightly closed during the immersing operation. A track 5 extends longitudinally into the immersing cylinder 1 and is provided with two branches 6 and 7, 110

which extend respectively into a pre-heating chamber 8 and a cooling or tempering chamber 9, Fig. 4.

The blocks 10 to be treated are mounted upon cars, one of which, designated by 11, is shown in the immersing cylinder 1, mounted on the track 5. Doors 12 and 13 are provided for closing the ends respectively of the preheating chamber 8. Doors 14 and 15 are provided for respectively closing the ends of the cooling chamber 9.

The immersing cylinder 1 is mounted in a furnace 16, which is provided in its lower portion with a horizontal longitudinal flue 17, which discharges upwardly between a plurality of parallel horizontal transverse baffling members 18 and against the under side of the cylinder 1.

Mounted in the furnace 16 above the immersing cylinder 1 is a supply tank 19 which is adapted to contain the supply of bituminous material with which the blocks 10 are to be impregnated. The tank 19 is supported upon transverse bars 20, the ends of which are supported by the walls of the furnace 16, and the middle portions of which may be supported by pillars 21, mounted on the cylinder 1. Horizontal shelves 22 extend longitudinally along the walls of the furnace 16 at opposite sides of and against the cylinder 1 from the rear end of the furnace to a point adjacent to the forward end of the cylinder 1. Shelves 23 extend longitudinally along the walls of the furnace 16 at opposite sides of and against the tank 19 from the forward end of the furnace to a point adjacent to the rear end thereof.

A burner 24 discharges into the rear end of the flue 17. The products of combustion from said burner pass forwardly through the flue 17, thence upwardly between the baffling members 18, thence forwardly to and around the forward ends of the shelves 22, thence upwardly and rearwardly over said shelves and against the tank 19, thence rearwardly to and around the rear ends of the shelves 23, and thence forwardly above said shelves into the smoke stack 25 with which the furnace 16 is provided. For supplementing the heat from the burner 24, burners 26 may be provided. These burners are arranged to discharge rearwardly between the cylinder 1 and the tank 19 at the forward end of the furnace 16. For heating the tank 19 interiorly, there are placed therein a plurality of steam pipe coils 27, one set of ends of which connect with a header 28, and the other set of ends of which connect with a header 29. The headers 28 and 29 and the coils 27 form a steam radiator, which is supplied with steam by a steam pipe 30, which connects with the header 28 and with the boiler of a steam producer 31, which, preferably, discharges its gaseous products of combustion into the

furnace 16 through a pipe 32. A pipe 33 is connected to the header 29 and to the boiler of the steam producer 31. For ascertaining the temperature of the interior of the cylinder 1, it may have extending from the outside into it thermometers 34 disposed at suitable places. Thermometers 35 are similarly provided for the tank 19. The baffling members 18 are preferably adjustable toward and from each other, those farthest from the burner 24 being spaced farther apart than these nearer to said burner.

For transferring the liquid bitumen from the tank 19 to the immersing cylinder 1, and for returning the bitumen to the tank 19, a conductor 36 is connected to the lower side of the cylinder 1 and is provided with two branches 37 and 38 which are respectively connected to the lower side and the upper side of the tank 19. Shut off valves 39 and 40 are respectively located in the branches 37 and 38.

Adjacent to the immersing cylinder 1 is an air pump 41 of any suitable type. Means are provided by which the pump 41 may exhaust air from the cylinder 1 or force air into said cylinder, as may be desired. For effecting these functions I have provided the following described mechanism: The pump 41 is provided with a cylinder 42 in which is mounted a reciprocative piston 43. A conductor 44 is connected to the upper side of the cylinder 1 and is provided with two branches 45 and 46 connected to the cylinder 42 adjacent to the respective ends thereof. In the branch 45 are located a shut off valve 47 and a check valve 48. In the branch 46 are located a shut off valve 49 and a check valve 50. The branch 45 is provided with a branch 51 open to the atmosphere and provided with a shut off valve 52 and a check valve 53. The branch 46 is provided with a branch 54 open to the atmosphere and having a shut off valve 55 and a check valve 56. The check valves 48 and 56 open toward the cylinder 42, and the valves 49 and 53 open away from the cylinder 42. Connected to the cylinder 42 adjacent to its respective ends are exhaust pipes 57 and 58 in which are respectively located shut off valves 59 and 60. When it is desired to exhaust the air from the cylinder 1, the door 2 is closed as are the valves 39 and 40. The valves 47, 52 and 60 are opened, and the valves 49, 53 and 59 are closed. The piston 43 is then reciprocated upon which air will be drawn from the cylinder 1 through the conductor 44 and branch 45 into the pump cylinder 42 and then discharged to the atmosphere through the branch 45 and branch 51. In pumping air into the cylinder 1, the valves 39, 40, 47, 52 and 60 are closed and the valves 49, 55 and 59 are opened. When the piston 43 is re-

ciprocated, air will be drawn into the pump cylinder 42 through the branches 46 and 54 and discharged into the cylinder 1 through the branch 46 and conductor 44. Connected 5 to the conductor 44 may be provided a pressure gage 61 and a vacuum gage 62 by which the air pressure in the cylinder 1 may be determined.

For the purpose of determining the level 10 of the immersing liquid in the immersing cylinder 1, there may be provided a float 63 having a vertical upwardly extending stem 64 vertically movable in the conductor 44 and adapted to enter the transparent 15 tension 65 with which the conductor 44 is provided.

Below the chambers 8 and 9 respectively are two longitudinal flues 67 and 66 respectively, which respectively discharge upwardly between baffling members 68, corresponding to the baffling members 18, into the pre-heating chamber 8 and cooling chamber 9. Discharging respectively into one set of ends of the flues 67 and 66 are 20 burners 69 and 70. A discharge conductor 71 having rotatively mounted in it an exhaust fan 72 has two branches 73 and 74 which respectively connect to the upper parts and right hand ends, as viewed in 25 Fig. 6 and Fig. 4 of the chambers 8 and 9. In the branches 73 and 74 are respectively mounted two swinging dampers 75 and 76, which respectively control the amount of air drawn from the chambers 8 and 9 by 30 the exhaust fan 72. By proper control of the burners 69 and 70 and of the dampers 75 and 76, temperatures respectively suitable for the purposes of the pre-heating chamber 8 and cooling chamber 9 may be 35 provided. The track 5, where it enters the immersing chamber 1, is provided with two removable rail sections, Fig. 4, which may be removed to permit of the closing and opening of the door 2.

40 In the operation of my invention, the door 12 is opened and cars, corresponding to the car 11, loaded with the blocks 10, which are to be treated, are run on the track 6 into the pre-heating chamber 8. This chamber may be retained at a temperature above the melting point of the filling material to be employed in impregnating the blocks. When the blocks are heated to the desired temperature, the doors 13 and 45 2 are opened, and the cars carrying the blocks are run into the immersing cylinder 1 upon the track 5. In the meantime, the burner 24 and the steam producer 31 have been operated so as to heat the immersing cylinder 1 to the proper temperature, and to heat the tank 19 sufficiently to melt the filling material which is contained therein. If the filling material is asphalt, the interior of the cylinder 1 and tank 19 will be 50 heated above the melting point of the asphalt,

54 the door 2 having been closed and tightly clamped by means of the securing devices 4, which may be swinging bolts provided with nuts, such as are commonly provided for purposes of this kind. The 58 pump 41 is then operated, in the manner hereinbefore described, to exhaust the air from the immersing cylinder 1. The shut-off valve 39 is then opened, thereby permitting the melted filling material to flow from the tank 19 through the conductor 36 and its branch 37 into the cylinder 1 until the blocks 10 in said cylinder are immersed. The valve 39 is then closed, and the pump 41 is operated to force air into the immersing cylinder 31. After a sufficient pressure has been produced in the cylinder 1, the valves 47 and 49 are closed, following which the blocks are permitted to remain in the cylinder 1 under pressure and immersed until their pores have been completely filled with the immersing liquid. The valve 40 is then opened and also the valve 49 and valves 55 and 59, and the pump 41 is again operated to pump air into the 65 cylinder 1. The air pressure in said cylinder will force the liquid filling material from the cylinder 1 through the conductor 36 and branch 38 into the tank 19. After the cylinder 1 has been emptied of the 70 liquid filling material, the door 2 is opened, the rail sections 77 put in place and the cars 11 loaded with the impregnated blocks 10 are run over the branch track 7 into the cooling chamber 9, the door 15 thereof being opened for this purpose. After the cars have been run into the cooling chamber, the door 15 is closed, and the blocks are allowed to remain in the cooling chamber until the filling material has solidified. 75 During this period of time, the temperature in the cooling chamber 9 is retained below the melting point of the filling material, and at a point sufficiently high above atmospheric temperature to prevent the sudden cooling of the blocks and the consequent chilling of the impregnating material which covers the exterior of the blocks. As the impregnating material gradually cools, it will, by reason of its coefficient of expansion being greater than that of the blocks, if such blocks are brick or similar material, contact to a greater extent than the blocks, whereby the coating of the impregnating material on the exterior of the blocks 80 will be drawn into the pores of the blocks, so that when the blocks have been cooled sufficiently to solidify the impregnating material contained therein, the blocks will not stick together but may be easily separated after the door 14 has been opened and the cars have been run out of the cooling chamber. While the cooling operation is being carried on, an instalment of pre-heated 85 blocks may be undergoing immersion in the 90 cylinder 1.

chamber 1, and another set of blocks may be, at the same time, undergoing the pre-heating operation in the chamber 8. The operation may thus be made practically 5 continuous, thereby effecting a great saving in fuel and time and a large increase in the output of the apparatus. By reason of the contiguity of the chambers 8 and 9, the heat from the chamber 8 may be employed 10 by conduction for assisting in heating the chamber 9.

Various modifications of my invention, within the scope of the appended claims, may be made without departing from its 15 spirit.

What I claim is:—

1. The method consisting in saturating a porous block with a substance having a greater coefficient of expansion than the 20 block and which is liquefied by heat and solidifies at ordinary temperatures, and then gradually cooling the block at a temperature below the melting point of the substance and above the ordinary atmospheric temperature, the cooling of the block being effected at substantially atmospheric pressure.

2. The method consisting in forcing by pressure greater than atmospheric into the pores of a porous block a substance liquefied 30 by heat and which solidifies at ordinary temperatures and has a greater coefficient of expansion than the block, and then gradually cooling the block at a temperature below the melting point of the substance and 35 above the ordinary atmospheric temperature, the cooling of the block being effected at substantially atmospheric pressure.

3. The method consisting in saturating a porous block with liquid bitumen having a 40 greater coefficient of expansion than the block, and then gradually cooling the block at a temperature below the melting point of the bitumen and above ordinary atmospheric temperature, the cooling being effected 45 at substantially atmospheric pressure.

4. The method consisting in forcing into the pores of a porous block liquid bitumen having a greater coefficient of expansion than the block, and then gradually cooling 50 the block at a temperature below the melting point of the bitumen and above ordinary atmospheric temperature, the cooling being effected at substantially atmospheric pressure.

5. The method consisting in saturating a porous block with liquid asphalt having a coefficient of expansion greater than the block, and then gradually cooling the block at a temperature below the melting point of 60 the asphalt and above ordinary atmospheric temperature, the cooling being effected at substantially atmospheric pressure.

6. The method consisting in forcing liquid asphalt under pressure greater than atmospheric into the pores of a block having a

coefficient of expansion less than that of the asphalt, and then gradually cooling the block at a temperature below the melting point of the asphalt and above ordinary atmospheric temperature, the cooling being 70 effected at substantially atmospheric pressure.

7. The method consisting in saturating a brick with liquid asphalt, and then gradually cooling the brick at a temperature below the melting point of the asphalt and above ordinary temperature, the cooling being effected at substantially atmospheric pressure.

8. The method consisting in forcing liquid asphalt under pressure greater than atmospheric into the pores of a brick, and then gradually cooling the brick at a temperature below the melting point of the asphalt and above ordinary temperature, the cooling being 85 effected at substantially atmospheric pressure.

9. The method consisting in heating a porous block, then exhausting the air from the block, then forcing liquid bitumen having a coefficient of expansion greater than the block into the pores of the block, and then gradually cooling the block at a temperature below the melting point of the bitumen and above ordinary atmospheric 95 temperature, the cooling being effected at substantially atmospheric pressure.

10. The method consisting in heating a porous block, then exhausting the air from the block, then forcing liquid asphalt having a coefficient of expansion greater than the block into the pores of the block and then gradually cooling the block at a temperature below the melting point of the asphalt and above ordinary atmospheric 100 temperature, the cooling being effected at substantially atmospheric pressure.

11. The method consisting in heating a porous block, then exhausting the air from the block, then forcing liquid bitumen under 110 pressure greater than atmospheric into the pores of the block, the bitumen having a coefficient of expansion greater than the block, and then gradually cooling the block at a temperature below the melting point of the bitumen and above ordinary atmospheric 115 temperature, the cooling being effected at substantially atmospheric pressure.

12. The method consisting in heating a porous block, then exhausting the air from the block, then forcing liquid asphalt under pressure greater than atmospheric into the pores of the block, the asphalt having a coefficient of expansion greater than the block, and then gradually cooling the block at a 120 temperature below the melting point of the asphalt and above ordinary atmospheric temperature, the cooling being effected at substantially atmospheric pressure.

13. The method consisting in heating a 130

brick, then exhausting the air therefrom, then forcing liquid bitumen into the pores thereof, and then gradually cooling the brick at a temperature below the melting point of the bitumen and above ordinary atmospheric temperature, the cooling being effected at substantially atmospheric pressure.

14. The method consisting in heating a
10 brick, then exhausting the air therefrom,

then forcing liquid asphalt into the pores thereof, and then gradually cooling the brick at a temperature below the melting point of the asphalt and above ordinary atmospheric temperature, the cooling being effected at substantially atmospheric pressure. 15

In testimony whereof I have signed my name to this specification.

CLAUDE FULLER.
